(57) **CLAIM**

The ornamental design for a display screen or portion thereof with graphical user interface, as shown and described.

DESCRIPTION

FIG. 1 is a front view of a display screen or portion thereof with graphical user interface according to a first embodiment of the claimed design.

FIG. 2 is a rear view of the display screen or portion thereof with graphical user interface of FIG. 1.

FIG. 3 is a left side view of the display screen or portion thereof with graphical user interface of FIG. 1.

FIG. 4 is a right side view of the display screen or portion thereof with graphical user interface of FIG. 1.

FIG. 5 is a top view of the display screen or portion thereof with graphical user interface of FIG. 1.

FIG. 6 is a bottom view of the display screen or portion thereof with graphical user interface of FIG. 1; and,

FIG. 7 is a front view of a display screen or portion thereof with graphical user interface according to a second embodiment of the claimed design.

The dash-dot-dash broken lines in FIGS. 1-7 showing the display screen illustrate environmental subject matter that forms no part of the claimed design.

The dash-dash broken lines and long-dash double-short-dash broken lines in FIGS. 1 and 7 illustrate portions of the graphical user interface that form no part of the claimed design.

The stipple shading in FIG. 7 depicts a contrast in appearance.
